UNITED STATES PATENT OFFICE.

THOMAS WALLACE, OF WABASH, INDIANA.

ELECTRICALLY-HEATED PRESSING AND LAUNDRY IRON.

Application filed January 7, 1921. Serial No. 435,713.

Generally stated, my invention relates to laundry and pressing irons that are heated by electricity passing through certain of their internal parts, and consists of means 5 for automatically breaking the circuit between the terminals, when the irons are not in use, together with means for automatically completing the circuit when pressure is applied to the handle of the iron during use. 10 My object then is, to provide an iron that if left on inflammable material, cannot generate enough heat to start a fire. An electrically heated flat-iron containing my improvements can be left on clothing or wood-work and the moment the hand of the user is taken off the iron the current is automatically shut off, also when the user commences to use the iron the current is automatically supplied to the heating unit of the iron. 15 Another advantage is that there is a considerable saving in the cost of heating the iron. In combination with the iron I provide a special stand and other means for getting the iron hot without holding the iron in the hand until it is hot enough for use.

Briefly stated, Fig. 1 is an internal and sectional view showing the means for automatically breaking the circuit. Fig. 2 is an end part-elevation of the handle. Fig. 3 shows the formation of the top end of the rod 4. Fig. 4 is a part vertical section on the line 4—4 on Fig. 1 and viewed in the direction of the arrows. Fig. 5 is a plan of the switches, with the rod 4 removed. Fig. 6 is a vertical section on the line 6—6 on Fig. 5 and viewed in the direction of the arrows of the switch plates 6 and 7 with the rod 4 and the member 8 removed. Fig. 7 is a view of a flat iron stood on end showing how the 20 switch-bar 11 is actuated by contact with the surface upon which it stands and the weight of the iron. Fig. 8 is a plan view of the iron on a special stand. Fig. 9 is an end view of Fig. 8. Fig. 10 shows a modification of the foregoing, the automatic circuit breaker is placed in the handle of the iron, instead of the body.

Referring more particularly to the different drawings in which the numerals denote the same parts throughout, Fig. 1 shows my invention in the form as preferred by me. Parts 1, 1, Figs. 1, 4, and 8 are terminals for holding the contact plug 16, Fig. 7 and 9. Parts 2, 6, 7 and 14 are switch or contact-plates which when brought into contact with each other, by means of pressure

on the handle 3, down the rod 4, or along the rod 11, completes the circuit between the terminals 1, 1. The iron is formed with up-standing supports 20 at its opposite ends 60 (one only of which is shown) and the handle 13 contains a rod 18 one end of which extends through a vertical slot 17 in one of the supports 20 shown in Fig. 1; 19 is a recess in the end of the handle 3 permitting the 65 handle to be pushed down a distance of about $\frac{1}{8}$ of an inch, when the iron is in use. The rod 4 attached at its upper end to the handle 3 by means of the bolt or pin 18 passing through the eye of the rod 4 Fig. 3, causes 70 the rod to descend upon the switch plate 6 and thereby complete the circuit between the terminals 1, 1.

When the user takes his hand off the handle of the flat-iron the spiral spring 5 pushes 75 the handle 3 back into the position as shown at Figs. 1 and 2 automatically breaking the electrical circuit between the terminals 1, 1.

The rod 4 is screwed into the top plate 2 as shown at Figs. 1 and 6. 8, Fig. 1, is the 80 electrical connection between the switch plate 6 and whatever heating unit may be used in the body of the flat iron. 25, Figs. 1 5 and 6, are various insulators. 33, is an insulating collar for the terminals 1, 1, Fig. 85 1, 9, Fig. 1, is the inside iron.

10, Figs. 1 and 4 is a support for the rod 11. 12, is a spiral spring to cause automatic breaking of the circuit. 13 is a collar on the end of the rod 11. 15, Figs. 1, 7, 8 and 9 90 are legs screwed into the base-iron for use as shown at Fig. 7.

22, Fig. 9, is an upstanding support, attached at its bottom end to the stand and at its top end carrying a pressure bar 24 95 pivotally connected by the member 23, and pressing on the handle 3. This enables the user to heat the iron without holding it in the hand. Also the pivotal connection of the bar 24 causes it to swing out of use when 100 the iron is taken off the stand. When the bar is required to connect the current, it must be placed there purposely.

Figure 10, shows a modification of the means for automatically breaking or completing the electric circuit between the terminals. The handle 28 and 29 of the iron is here shown horizontally and centrally divided. The part 28 is caused to rise by means of the springs 27 opening the switch 110 plates 26 connected to the wires 30 which descend the handle support 24, to the connec-

tions 35 in the body 36 is a plate for holding the top part of the handle 28 in position. Any of the means well known to the state of the art, may be used for connecting the wires at 31.

The horizontal switch bar 11, and its switch plate 14 Fig. 1, is not essential to the true working of the plunger 4 and its switch plates 6 and 7.

10 What I claim as new, and desire to secure by Letters Patent is:—

1. In combination with a stand for a flat-iron, an upstanding support attached at its lower end to the stand, and a horizontal arm pivoted on said support on a substantially vertical axis for downwardly pressing upon the handle of a flat-iron positioned on said support.

2. In an electrically heated flat-iron having a switch for controlling the supplying of current thereto, comprising a relatively stationary contact member and two movable contact members, all of said members being normally out of contact, means for moving one of said movable contact members into engagement with said stationary contact member, and means operating automatically, when the iron is stood on end, to move the other of said movable contact members into engagement with both of the other contact members.

3. In an electrically-heated flat iron, the combination with its body portion of standards located at opposite ends thereof, a handle mounted on said standards and movable up and down thereon, a switch device mounted on the iron and formed of members normally spaced apart, a plunger operatively engaging said handle and adapted when depressed to close said switch, said switch automatically moving to open position when said plunger is elevated, and a spring surrounding said plunger and inter-

posed between the body of said iron and said handle for yieldingly holding said handle and plunger in elevated position.

4. In an electrically-heated flat iron, the combination with its body portion of standards located at opposite ends thereof, one of said standards containing a slot, a handle mounted on said standards, said handle having a portion which extends into said slot and is movable up and down therein, a switch device mounted on the iron and formed of members normally spaced apart, a plunger rod operatively engaging said portion of said handle and adapted when depressed to close said switch, said switch automatically moving to open position when said plunger is elevated, and a spring surrounding said plunger and interposed between the body of said iron and said handle for yieldingly holding said handle and plunger in elevated position.

5. In an electrically-heated flat iron, the combination with its body portion of standards located at opposite ends thereof, one of said standards containing a slot, a handle mounted on said standards, said handle comprising a body portion and a rod surrounded by said body portion of the handle and extending lengthwise of the latter, said rod extending into said slot and being movable up and down therein, a switch device mounted on the iron and formed of members normally spaced apart, a plunger-rod operatively engaging said first referred to rod and adapted when depressed to close said switch, said switch automatically moving to open position when said plunger is elevated, and a spring interposed between the body of the iron and said handle for yieldingly holding said handle and plunger in elevated position.

THOMAS WALLACE.
